AUTOMATIC INTERCOMMUNICATING
SYSTEM

William F. Davidson, St. Paul, Minn.

Application July 31, 1933, Serial No. 683,005

1 Claim. (Cl. 179—1)

The present invention relates to an automatic intercommunicating system.

In office buildings it is sometimes necessary for the occupants of an office to be absent during business hours, especially in some of the smaller offices, and when a customer or client calls at such an office and all of the occupants are out, the caller may leave and take his business elsewhere, with a consequent loss to the tenants of said office.

An object of the present invention is to make an improved and simplified intercommunicating system for office and similar use.

In order to attain this object, there is provided, in accordance with one feature of the invention, a two-way communicating system between a central station and a plurality of selectively energized substations, each of said substations having automatic signal means embodied therein to be actuated by an element associated with each of said substations.

These and other features of the invention will be more fully brought out in the following description and the accompanying drawing, 25 wherein:

Figure 1 is a schematic circuit drawing of an automatic intercommunicating system embodying the present invention.

Figure 2 is a view in front elevation of a loudspeaker used in the present invention.

Figure 3 is a view in front elevation of a microphone and housing therefor.

Figure 4 is a sectional view on the line 4—4 of Figure 3; and

Figure 5 is a fragmentary sectional view through a door and frame thereof, showing in elevation a switch mechanism mounted on the door frame to be actuated by the opening of said door.

Referring to the drawing in detail, a loudspeaker 1 is installed in a convenient location in a room or office in which the device is to be located, and a microphone 2 is mounted on a wall of the office, preferably opposite the entrance door to said office. This microphone is mounted in a housing 3 having an electric lamp 4 mounted therein to illuminate a transparent plate 5 mounted in the front of the housing 3.

A trip switch 6 is mounted on a door frame 7. The switch 6 comprises a support bracket 8 having a pair of normally open spring contact members 9 and 10 supported thereon. An arm 11 is pivotally mounted on the bracket 8 to normally lie in the solid line position shown in Figure 7. On opening a door 12 the arm 11 is engaged by

the door and moved to the dotted line position shown in Figure 5, thereby closing the contacts 9 and 10.

The circuit employed in the present embodiment of the invention is shown in Figure 1.

From a ground 13, a conductor 14 is connected to the contact member 10. From the other contact 9, associated therewith, a conductor 15 is connected through a switch 66 and conductor 67 to the coil of a conventional drop leaf signal 16, the other end of said coil being connected by a conductor 17 to a battery 18, from which a conductor 19 is connected to ground 20. A drop leaf 21 is mounted to be released upon operation of the relay 16, said drop leaf, when released, making contact with a conductor 22 which is connected to one terminal of a buzzer 23, the other terminal of said buzzer being connected by a conductor 24 to a battery 25. From the other terminal of battery 25 a conductor 26 is connected to the drop leaf 21.

The microphone circuit for the microphone 2, which is located in the office to be served, leads from ground 13, through conductor 14, conductors 27 and 28 to the microphone 2, whence a conductor 29 is connected to a contact 30 of a selector switch. The arm 31 of this switch is connected by a conductor 32 to one terminal of the primary coil 33 of a transformer. A conductor 34 is connected from an intermediate point of the primary coil 33 to a switch 35. From this switch a conductor 36 is connected to one terminal of a battery 37, a conductor 38 being connected from the other terminal of this battery to ground 39.

A secondary coil 40 is associated with the primary coil 33 to form a transformer and from the secondary coil 40 conductors 41 and 42 are connected to the input side of an audio amplifier 43 of a well known type. From an output terminal 44 of the amplifier 43, a conductor 45 is connected to a conductor 46 which is connected to conductors 27 and 14 to ground 13. A conductor 47 is connected to the loudspeaker 1, conductor 48, a selector switch 49, conductor 50 to output terminal 51 of the amplifier 43.

A headset 52 is connected by conductors 53 and 54 to conductors 45 and 50, respectively. An end of the transformer primary coil 33 is connected by a conductor 55 to a transmitter 56, which is also connected by a conductor 57 to ground 58.

Conductors 59 and 60 are connected to the power supply terminals 61 and 62, respectively, of the amplifier 43, and these conductors are 55

connected to a suitable supply of altering electrical current.

A separate circuit is provided for the lamp 4, wherein conductors 63 and 64 connect the lamp 4 to a battery 65.

Operation

When a tenant having the present arrangement installed in his office is about to leave the office and desires to place the mechanism in operative condition, he closes the switch 66, and opens the door 12 and walks over to the microphone. The opening of the door 12 closes the contacts 9 and 10, thereby completing a circuit 15 from ground 13, through conductor 14, contacts 9 and 10, conductor 15, switch 66, conductor 67, coil of the relay 16, conductor 17, battery 18, conductor 19, to ground 20. This energizes relay 16 and drops the leaf 21 which closes the buzzer 22 circuit through conductor 22, the buzzer 23, conductor 24, battery 25, conductor 26, and the drop leaf 21.

The operator then throws selector switches 30 and 49 to the contacts of the circuit indicated by 25 the relay 16, in a well known manner, and closes the switch 35. These three switches may all be operated as a single unit, or may be connected to a jack in a manner well known to the art.

The operator then says "good morning", or 30 other suitable greeting, and pauses, the operator speaking into the transmitter 56, which is connected by conductor 57 to a ground 58, and on the other side through conductor 55, primary coil 33, conductor 34, switch 35, conductor 36, battery 37, conductor 38, to ground 39. The current fluctuations set up by the transmitter 56 induce currents in the secondary transformer coil 40 and are carried by the conductors 41 and 42 to the amplifier 43. From the amplifier, the amplifier currents 40 pass through conductors 45, 46, the loud-speaker 1, conductor 48, switch 49, and conductor 50, the loudspeaker transmitting the message "good morning" to the subscriber's office. The subscriber then speaks into the microphone 2, 45 saying, as an example, "I am leaving the office now and will return in about thirty minutes."

The microphone is connected on one side by conductors 28, 27, and 14 to ground 13, and on the other side through conductors 29, the switch 50 contact 30, switch arm 31, conductor 32, primary coil 33, conductor switch 35, conductor 36, battery 37, and conductor 38 to ground 39.

This induces an oscillating current in the secondary coil 40 which current is conducted through the amplifier 43 as above set forth to conductors 45 and 51 from whence conductors 53 and 54, respectively, carry the current to the headset 52. 5

The operator then opens the switches 30, 35, and 49.

If, during the absence of the tenant a caller opens the door 12, the contacts 9 and 10 will be closed, thereby actuating the drop signal 21 and 10 the buzzer 23 as above set forth. The operator then closes the switches 30, 35, and 49, and speaks into the transmitter 56, say, as an example, "Good morning, Mr. Blank is out, but will return in about thirty minutes. Will you kindly step over to the microphone on the wall in front of you and give me your message?" 15

The caller's attention is directed by the illuminated panel 5 to the microphone and he steps over to the microphone and says, for example, "Tell Mr. Blank, please, that Mr. Brown called and ask him to phone my office when he returns." 20

The operator then replies, "Thank you, I will tell him."

When the tenant returns he steps over to the microphone and after the operator has completed her routine greeting, the tenant speaks into the microphone 2, "This is Mr. Blank, have you any messages for me?" 25

The operator then gives the tenant any messages she may have for him. The tenant opens the switch 66, and the mechanism is thereby rendered inoperative until the switch 66 is again closed. 30

I claim:

An automatic secretarial inter-communicating system of the class described, comprising in combination a central station having a receiver and a transmitter, a sub-station in a room remote from said central station, said sub-station having a 40 loud speaker receiver and a microphone transmitter, switch means operable from the sub-station to connect the central station with the sub-station, a signal located at the central station, and signal operating means mounted in the sub-station and automatically operable by the entrance of a person into the sub-station to actuate said signal in the central station and secondary switch means operable from the sub-station to render said signal operating means inoperative, 45 for the purpose set forth. 50

WILLIAM F. DAVIDSON.
